CLAIM

The ornamental design for a cutting device for masking film, as shown.

DESCRIPTION

FIG. 1 is a front perspective view of a cutting device for masking film showing my new design;

FIG. 2 is a front elevational view;

FIG. 3 is a right side elevational view;

FIG. 4 is a rear elevational view;

FIG. 5 is a left side elevational view;

FIG. 6 is a top plan view;

FIG. 7 is a bottom plan view; and

FIG. 8 is a cross-sectional view taken along the central vertical line of FIG. 2.

The "cutting device for masking film" appears as is shown in the drawings.

FIG. 1

FIG. 2

FIG. 3

FIG. 4

FIG. 5

FIG. 6
